ADJUSTING GAUGE DEVICE FOR PRINTING
PLATE BORING MACHINES

Robert V. Bruckshaw, Centerville, Iowa

Application August 5, 1935, Serial No. 34,792

1 Claim. (Cl. 33—185)

In the art of newspaper printing and the like it is the custom at the present time to form cast type metal cylindrical printing plates. These plates are then used in the cylindrical printing 5 plate press. These cylindrical printing plates are cast of type metal, and it is very important that the printing plate be of uniform thickness throughout. Otherwise, it will result in imperfect printing.

Considerable difficulty has been encountered in forming the interiors of these cylindrical printing plates accurately enough for high grade printing. This turning out of the interior printing 10 plate is customarily accomplished on an ordinary turning lathe, and frequently the most skilled operators of these turning lathes make defective printing plates.

The object of my invention is to provide a gauge device of simple, durable and inexpensive construction which may be employed by the operator 20 in connection with these lathes for turning the interiors of the printing plates in such manner that the operator may quickly, readily and easily adjust his turning lathe and tool in such manner 25 as to cause the turning lathe to turn out the interior of the printing plate with great accuracy under all circumstances.

My invention consists in the construction of a gauge device and in its arrangement in combination with a turning lathe whereby the objects 30 contemplated are attained, as hereinafter more fully set forth, pointed out in my claim, and illustrated in the accompanying drawing, in which:

Figure 1 shows a perspective view of my improved gauge device; and

Figure 2 shows a vertical longitudinal view of a portion of a lathe for tubular plate finishing machines having my improved gauge device applied thereto.

Referring to the accompanying drawing, I have used the reference numeral 10 to indicate generally a turning lathe of the kind ordinarily used in connection with the turning of printing plates. This lathe has at one end a cylinder 11, and on 45 the interior of the cylinder is a lining 12, preferably made of brass and turned to great accuracy to exactly fit the exterior of a cylindrical printing plate. This cylinder and lining are rotated in a manner not shown, which, however, is in common 50 use on lathes of this character.

The turning tool comprises a stationary shaft 13 having a slidable collar 13a thereon, having one or more lathe tools 14, of ordinary construction carried thereby. This collar 13a may be advanced and retracted through the cylinder 11 by

means of a rack 14a and pinion 14b. These tools may be adjusted radially of the collar by the adjusting device 14c and may be fixed in any position of adjustment by the screws 14d. This turning tool adjusting mechanism is of the ordinary construction now in common use.

My improved gauge comprises a cylindrical body portion 15 having at one side thereof two parallel radially extended posts 16 and 17. Mounted upon these posts is a gauge arm indicated generally by the numeral 18. This arm has openings for the posts 16 and 17, and on the post 17 the arm has a sleeve 19 to aid in maintaining the arm 18 exactly at right angles to the post 17 during the up and down movements of the gauge 15 arm. At the top of the post 17 is a head member 20 to which the posts are attached, and extended through this head member is a screw 21 seated, that is to say, mounted in a screw threaded opening in the gauge arm 18 and rotatably mounted 20 at its lower end within the base 15 and is held against longitudinal movement in the head and base in any ordinary way.

The gauge arm 18 is very carefully constructed so that its thickness from its outer to its inner 25 face is exactly that of the thickness to which the printing plates are to be turned.

In practical use a printing plate to be turned is placed on the interior of the brass cylinder 12 and there supported in the customary way. 30 Then the gauge device is supported on the shaft 13 with its arm 18 extended into the interior of the cylinder 11, then the screw 21 is turned until the outer face of the arm 18 is parallel with the inner surface of the brass cylinder 12, and when in 35 this position the arm 18 is adjacent the end of the printing plate. After this has been done, the lathe tools 14 are adjusted to position where they just touch the inner surface of the gauge arm 18, as shown in Figure 2. This gauge arm is adjustable, as before stated, and may be adjusted to 40 position in engagement with the brass cylinder or spaced apart therefrom. Then the gauge device is removed and the cylindrical printing plate has its interior turned out by the lathe in the ordinary manner.

I have found that with my improved gauge device an ordinary operator will turn out the interiors of the printing cylinders with great accuracy with the result that the cylindrical 50 printing plates are all of substantially the same thickness, resulting in an improved job of printing therefrom.

I claim as my invention:

A gauge device for printing plate boring ma- 55

chines comprising a cylindrical body portion adapted to be removably and slidably mounted upon the sliding collar of a printing plate boring machine, two posts fixed to and extended radially from said cylindrical body, a head member fixed to the outer ends of said posts, a gauge arm slidably supported by said posts and projected at one end beyond the cylindrical body, an adjusting screw rotatably mounted in the said head and

body extended above the head and passed through a screw threaded opening in the arm, and whereby the arm may be set to position for turning printing plates to the desired thickness and the gauge device left in said set position and repeatedly applied to and removed from the boring tool so that a series of printing plates may be turned to the same thickness.

ROBERT V. BRUCKSHAW.
